UNITED STATES PATENT OFFICE.

HERMANN SCHULZE-BERGE, OF ROCHESTER, PENNSYLVANIA.

APPARATUS FOR THE MANUFACTURE OF GLASSWARE.

SPECIFICATION forming part of Letters Patent No. 439,196, dated October 28, 1890.

Application filed October 9, 1889. Serial No. 326,489. (No model.)

To all whom it may concern:

Be it known that I, HERMANN SCHULZE-BERGE, of Rochester, in the county of Beaver and State of Pennsylvania, have invented a 5 new and useful Improvement in Apparatus for the Manufacture of Glassware, of which the following is a full, clear, and exact description.

The present specification describes certain 10 improvements in the fire-melting and finishing of glassware; and it consists in apparatus comprising a glory-hole furnace with means for manipulating the glass object therein.

The special feature of the present invention 15 is a finishing-tool adapted to be applied to the reheated glass while the latter is as yet in the fire-chamber or flue of the glory-hole, and other requirements necessary for such operation, as hereinafter described.

20 My improved apparatus is represented in the accompanying drawings, in which—

Figure 1 represents a vertical longitudinal section of the apparatus. Fig. 2 is an enlarged sectional view. Fig. 3 is a vertical 25 longitudinal section of a modified form. Fig. 4 is an enlarged longitudinal section of part thereof.

Like symbols of reference indicate like 30 parts in each.

35 As shown in Fig. 1, the glory-hole furnace comprises a fire-chamber 2, a burner 3 or suitable combustion-chamber, and a flue 4 for carrying off the products of combustion. I have shown the furnace resting upon iron standards, which, if desired, may be provided 40 with wheels, so as to render the apparatus easily portable. The fire-chamber 2 is provided with two glory-hole openings 5 and 6, located on opposite sides of the walls and in line with each other, so as to allow a supporting-rod inserted into the furnace through one opening to be pushed through the fire-chamber and to protrude with its head through the second or opposite glory-hole. This arrangement 45 affords several advantages over the form of furnace in use at present. It allows the glass object to be placed on and removed from or manipulated on the supporting-rod, while the latter protrudes through the second glory-hole opening, thereby giving an easy access 50 to the glory-hole not obstructed by machinery

or bearings, &c., and it allows also a finishing-tool to be inserted through such second opening into the fire-chamber in line with the revoluble supporting-rod. This is represented 55 in Fig. 1, which shows a glass lamp-chimney placed upon a revoluble supporting-rod and situate in the glory-hole 5. The chimney is placed on this rod while it is projecting through the fire-chamber out of the glory-hole 6, and 60 it is then drawn back into the position shown in the drawings. The supporting-rod 7 is supported in bearings 8 and 9 and passes through a driving-wheel which is journaled in fixed bearings 12. The bearing 9 is fixed or stationary; but the bearing 8 is supported in such manner as to be movable to and from the furnace, so as to carry the rod with it in such movement. The rod is thus moved by a lever 13, which is connected with the bearings 8 by 65 a rod 14.

In order to afford means for keeping the rod cool, I make it hollow, and make its head 15, which receives and supports the glass article, also hollow, (see Fig. 2,) and a water-in- 75 let pipe 16 extends to or nearly to the head, while a water-discharge pipe 17 leads from the rear end of the rod. A continuous circulation of water (or other cooling medium, such as air) may thus be maintained through the 80 rod and head, thereby preventing the sides of the glass article from becoming unduly hot and sticking to its support.

In front of the glory-hole 6 is a tool 18, adapted to be used in flaring the end of the 85 glass article after the latter has been softened by the heat of the furnace. For this purpose the supporting-rod 7 may be pushed through the furnace, so as to protrude through the glory-hole 6 and to engage the flaring-tool, or (what 90 is more desirable) the latter may be pushed through the glory-hole 6 to engage the glass article while the latter is still in the furnace. The advantage of the latter-named mode arises from the fact that when the glass article is in 95 the furnace and engaged by the shaping-tool it need not be heated to such high temperature as when the shaping is done outside the furnace, and there is therefore less liability to loss by misshaping of the overheated glass. 100

The shaping-tool 18 is carried at the end of a shaft or rod 19, which is supported in bear-

ings 20 21, and is driven by a crank-shaft 22 and pulley-wheels 23 and 24. The rod is adapted to slide longitudinally through the pulley-wheel 24 and is connected therewith by a feather-and-spline connection.

25 is a ratchet-wheel fixed to the shaft 22 and provided with a suitable pawl or lock, (not shown,) by which the crank-shaft and the rod and shaping-tool may be held stationary when necessary. The driving-wheel 10 of the rod 7 is driven by a belt 26, and its face is formed as or provided with a clutch-disk which engages the face of a clutch-disk 27, situate on the rod and connected therewith by a feather-and-spline connection 11, the clutch-disks being maintained in contact by means of a spring 28, interposed between the bearings 9 and the clutch-disk 27, so that normally the supporting-rod is rotated continuously on its longitudinal axis. The length of the feather 11 is so proportioned that when the supporting-rod 7 is pushed through the furnace far enough to bring the glass article into contact with the shaping-tool 18 on the other side thereof the feather shall pass the keyway in the clutch-disk, and no motion shall therefore be transmitted to the rod by the rotation of the driving-wheel.

Instead of the driving-wheel 10 as a means for transmitting rotary motion to the supporting-rod, stepped cones or similar driving-gear of the usual sort may be substituted, so that the motion of the rod may be variable to a greater or less speed, as may be desired.

35 In using the apparatus in the manner first above described the glass article, after it has been heated to a proper degree while in the position shown in Fig. 1, is advanced through the furnace by proper movement of the lever 40 13 until its end extends through the glory-hole 6 and engages the shaping-tool 18, which may then be rotated by driving the crank-shaft 22. When the end of the article has been flared or shaped, the glass article is removed, another article is placed in the head 45 of the supporting-rod 7, and the latter is drawn back, so as to place the glass article in the furnace and to subject it to the heat.

In Figs. 1 and 2 I show the apparatus as used in the manufacture of lamp-chimneys. The apparatus shown in Fig. 3 shows similar apparatus applied to fire-melting and finishing of glass tumblers. In this case the two supporting-rods arranged in line with each other are adapted to hold the tumbler between them in the furnace, the end of one rod bearing against the outside of the bottom of the tumbler and the other bearing against the inner side of the bottom. Such arrangement is 55 very desirable in holding the tumbler while its sides are subjected to the direct action of the heat. The first supporting-rod 7 is arranged similarly to the correspondingly-numbered rod described with reference to Fig. 1. The second supporting-rod 19 is provided with a swiveled head 28, as shown in Fig. 4. This rod is not necessarily revolute; but it may

be so. It is hollow and water-cooled, and is arranged to slide lengthwise in bearings which are connected with and are operated simultaneously with the frame supporting the bearings of the other supporting-rod 7. It may be separately moved in its bearings by the knee-lever 29, pivotally connected at 30 with the frame of the bearings, and it is normally pressed toward the glory-hole of the furnace by a spring 31. By turning this knee-lever on its pivot its supporting-rod 19 may be moved away from its companion rod 7, so as to permit an interposed tumbler to be removed or replaced.

The former or shaping-tool 32, which is mounted on the rod 19 back of the swiveled head 28, is adapted to be moved on the rod independently of the other mechanism by means of knee-levers 33, pivotally connected at 34 to the frame of the bearings. This tool is a thin-walled conical plug corresponding in size and shape to the inside of the finished tumbler. Any other suitable tool may, however, be substituted for it.

In order to place the tumbler between the ends of the supporting-rods, as shown in Fig. 4, and especially to remove it therefrom, I employ a spoon-shaped instrument, in which the tumbler is laid on its side, so that it shall not be liable to be injured or deformed while in a hot state.

The operation of the apparatus of Fig. 3 will be readily understood. The frame which supports the bearings of the rods is moved longitudinally, so as to introduce the glass article into the furnace or to withdraw it therefrom, by means of the hand-lever 13, which simultaneously moves both supporting-rods 105 longitudinally. When thus removed from the furnace, the glass article can be placed between or removed from the rods by moving the levers 29 and 33.

The advantages of my invention will be appreciated by these skilled in the art.

By use of my improvement the glass articles can be fire-finished and shaped more rapidly and with less labor than has hitherto been possible.

My invention may be modified in divers ways without departing from the principles thereof. Without therefore limiting myself precisely to the mechanical details shown and described—

I claim—

1. In apparatus for finishing glassware, a glory-hole furnace or flue provided with glory-hole openings, and a supporting-rod revolute and sliding in bearings in line with the glory-hole opening, in combination with a former or shaping-tool mounted on a rod and guided in bearings and adapted to be inserted into the fire-chamber or flue of the glory-hole furnace through separate openings into the path of the glass article.

2. A furnace for reheating or finishing glassware, having oppositely-situate lateral glory-hole openings, in combination with a

supporting-rod situate in front of one of said openings and adapted to be moved through both said glory-hole openings, substantially as and for the purposes described.

5 3. A furnace for reheating or finishing glassware, having oppositely-situate lateral glory-hole openings, in combination with a supporting-rod situate in front of one of said openings in bearings in which it is revoluble and adapted to be moved through both said glory-hole openings, substantially as and for the purposes described.

4. A furnace for reheating or finishing glassware, having oppositely-situate glory-hole openings, in combination with a supporting-rod situate in front of one of said openings and adapted to be moved through both said glory-hole openings, and a former or shaping tool adapted to be inserted through the opposite site glory-hole to meet the supporting-rod in the fire-chamber of the furnace, substantially as and for the purposes described.

5. A furnace for reheating or finishing glassware, having oppositely-situate glory-hole openings, in combination with a supporting-rod situate in front of one of said openings and adapted to be moved through both said glory-hole openings, and a second supporting-rod adapted to be inserted through the opposite site glory-hole to meet the first-named supporting-rod in the fire-chamber of the furnace, substantially as and for the purposes described.

6. A furnace for reheating or finishing glassware, having oppositely-situate glory-hole openings, in combination with a supporting-rod situate in front of one of said openings and adapted to be moved through both said glory-hole openings, a second supporting-rod adapted to be inserted through the opposite glory-hole to meet the first-named supporting-

rod in the fire-chamber of the furnace, and a shaping-tool adapted to engage and shape the glass article when held by said supporting-rod, substantially as and for the purposes 45 described.

7. In apparatus for reheating or finishing glassware, a supporting-rod having a head provided with hollow side walls for the circulation of a cooling medium, substantially as 50 and for the purposes described.

8. In apparatus for reheating or finishing glassware, the combination of the supporting-rod, with a former or shaping-tool movable longitudinally thereon, substantially as and 55 for the purposes described.

9. The combination of two supporting-rods journaled in the same axial line and movable toward or away from one another, adapted to receive and revolve a hollow glass object, with 60 a former or shaping-tool adapted to slide longitudinally on one of the supporting-rods.

10. The combination of a longitudinally-movable supporting-rod and mechanism for revolving it, with a former or shaping-tool in 65 the same axial line, and adapted to be moved longitudinally, substantially as and for the purpose described.

11. The combination of the supporting-rods 7 and 19, one at least of which is longitudinally movable in its bearings, and a movable frame connecting their bearings, so that both rods may be simultaneously moved lengthwise in the same direction, substantially as 70 and for the purposes described.

In testimony whereof I have hereunto set my hand this 23d day of September, A. D. 1889.

HERMANN SCHULZE-BERGE.
